VEHICLE PARKING DEVICE

Herman S. Johns, Oklahoma City, Okla., assignor
to Wiley W. Lowrey, Oklahoma City, Okla.

Application September 20, 1937, Serial No. 164,728

22 Claims. (Cl. 194—9)

This invention relates to new and useful improvements in vehicle parking devices.

This application is filed as a continuation-in-part of my co-pending application filed November 4, 1936, Serial No. 109,107.

In recent years, many larger cities throughout the country have installed vehicle parking devices, generally known as parking meters, on their streets to control the parking problem in congested business districts. The payment of a nominal sum by the motorist entitles him to park his vehicle in a designated place for a predetermined length of time, after which he must deposit another coin or relinquish his parking space. The primary purpose of the parking meter is not a source of revenue, but is to discourage the practice of one motorist occupying a particular parking space for several hours at a time, whereby several motorists may utilize the same space at different intervals or periods throughout the day, thereby resulting in a constant movement or replacement of the parked vehicles.

As is well known, the usual type of parking meter employs a movable indicator which is operated by a clock mechanism. The clock mechanism is actuated by the insertion of a coin and continues to move the indicator until the period has expired, regardless of whether or not a vehicle is occupying the space adjacent thereto. Therefore, the motorist who deposits the coin and starts the indicator in its movement may leave the parking space after ten minutes and assuming the particular meter to be adjusted for a sixty minute period, the indicator would continue its movement for the remaining fifty minutes. A second motorist may then park on the unexpired time of another and need not deposit another coin until the indicator has completed its travel.

This type of meter which is now in general use, has fallen far short of its primary purpose due to the fact that instead of relieving traffic congestion, it has in many instances increased the same because the motorists are constantly cruising about in an attempt to locate a parking space having unexpired time which may be used without cost. Not only do the parking meters fail to relieve congestion but also a considerable portion of just revenue from them is lost due to the free use of time which has not been fully used by the previous motorist.

Another objectionable feature of the present type of meter is that the motorist may keep his vehicle in a particular space throughout an entire day provided he deposits another coin each

time the paid for period expires. In other words, the space may be occupied by one motorist throughout several periods, which defeats the purpose intended in that the constant change or replacement of vehicles in the parking places is not accomplished.

Further, the indicator of the present parking meter is comparatively small and it is difficult to determine the exact position of the same from any great distance. The disposition of said indicator is such that when viewed from an angle, the indication is not clearly visible and, therefore, the police officer or other official, as well as the motorist, must observe said indicator from a point directly opposite and comparatively close to the meter in order to be absolutely sure of the indication.

Some of the meters now in use have a window below the indicator through which the coin which has been deposited, is visible but since the window is comparatively small, being substantially the same size as the coin, it is almost indiscernible from a distance and in order to observe the same the observer must be in close proximity to the meter. This window is separate from the window through which the indicator is visible and an observer cannot see both the indication and the coin at a single glance which necessitates his halting opposite the meter in close proximity thereto, to determine the indication and observe that the coin is a proper one.

In actual use, the parking meters are located throughout the length of a street and one police officer may be assigned several blocks. Ordinarily, the officer checks the meters as he travels along the street in a vehicle and with the present type of meters it is almost impossible to determine the indication on said meters without stopping opposite said meters. Many times, the sun or shadows throw a reflection on the windows and the officer must approach within a few feet of the meter to determine the indication.

From the above, it will be seen that the present types of parking meters which are now in general use, have many disadvantages which tend to defeat their purpose and it is, therefore, one of the objects of the present invention to provide a vehicle parking device which will overcome these disadvantages, as well as the other objections present in the usual meters.

An important object of the invention is to provide an improved parking meter which is controlled by the presence or absence of a vehicle in the parking space adjacent thereto, whereby each time a vehicle leaves said space the meter

is cleared and returned to starting position, regardless of whether or not the vehicle has remained in the space throughout the entire parking period, thereby eliminating any unexpired time on the indicator and consequently obviating cruising by the motorists in an attempt to locate a meter having such unexpired time; such arrangement forcing each motorist to deposit a coin when he parks his vehicle in a designated parking space.

Another object of the invention is to provide an improved parking meter which is constructed so that it cannot be operated unless a vehicle is properly parked in the space adjacent thereto, whereby the motorist must properly park his vehicle before the meter can be actuated.

A particular object of the invention is to provide an improved parking meter which is controlled by the presence of the vehicle in the parking space adjacent thereto which is so arranged that after the allotted time or parking period has expired, the meter cannot be further actuated until the vehicle in said space has been moved to clear the meter and return it to its starting position, whereby the practice of the motorist occupying the space for a greater length of time than one parking period merely by inserting another coin, is eliminated.

Still another object of the invention is to provide an improved parking meter having a single illuminated signal which is dimly lighted when no vehicle is in its space and which flashes when a vehicle enters said space to indicate that the vehicle is properly parked but no coin has been inserted; insertion of the coin extinguishing the signal which becomes brightly illuminated when the paid for parking period has expired to indicate the expiration of the allotted time, the signal returning to a dim glow when the vehicle is removed to indicate that the parking space is unoccupied. The use of the illuminated signal making it possible to observe the meter from a distance to ascertain the condition of the meter, whereby it is not necessary to closely approach said meter to determine if the vehicle is properly parked and the parking time paid for.

A particular object of the invention is to provide an improved parking meter having a recessed window or windows through which the indicating dial or dials are clearly visible, said dial or dials having an opening therein with means for retaining the coin which has been deposited to operate the meter, in alinement with said opening whereby the dial or dials and the coin are clearly visible through the opening or openings; the recessing of said opening or openings preventing sun rays or reflections from interfering with the visibility of the dial and coin.

A particular object of the invention is to provide an improved parking meter which is electrically operated and which is provided with a magnetic element in its base adjacent the parking space for the vehicle, whereby the area of stress or magnetic field between the poles of said element is located within the parking space so that a vehicle entering said space will enter the field and act upon the magnetic element to cause the same to operate certain of the electrical apparatus controlling the meter; the magnetic element being so arranged as to co-act with the coin receiving unit of the meter, whereby the element and the coin co-act to complete the operation of said meter, thereby making the operation of the meter dependent upon the presence or absence of a vehicle within the parking space.

A still further object of the invention is to provide an improved parking meter of the character described, which has its time indicating mechanism actuated by an electrical impulse whereby accuracy of the indication is assured and the operation is not affected by weather or other conditions; the construction of the meter being such that it may be electrically connected to a single source of time impulse along with a plurality of other meters so that all the meters are actuated by the single impulse; there being means provided within each meter for electrically disconnecting it from the impulse source when the same is not in use, such disconnection having no effect on the operation of the other meters in the circuit.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an elevation of a vehicle parking device, constructed in accordance with the invention,

Figure 2 is a similar view, taken at right angles to Figure 1,

Figure 3 is an enlarged, transverse, sectional view, taken on the line 3—3 of Figure 1,

Figure 4 is a face view of one of the side plates of the coin receiving and dial unit,

Figure 5 is a transverse, vertical sectional view, taken on the line 5—5 of Figure 3,

Figure 6 is a transverse, vertical, sectional view, taken on the line 6—6 of Figure 3,

Figure 7 is a transverse, vertical, sectional view, taken on the line 7—7 of Figure 3,

Figure 8 is a face view of the side plate opposite the plate shown in Figure 4,

Figure 9 is a longitudinal, vertical, sectional view taken on the line 9—9 of Figure 8,

Figure 10 is an enlarged view, partly in section and partly in elevation of the upper portion of the device,

Figure 11 is a wiring diagram,

Figure 12 is an enlarged, vertical, sectional view of the lower portion of the device and showing the wheel of a parked vehicle within the parking space to indicate the relation of the vehicle to the device,

Figure 13 is a sectional view of another form of magnetic control element, and

Figure 14 is a partial, horizontal, cross-sectional view taken through the locking mechanism.

In the drawings (Figures 1, 2 and 12), the numeral 10 designates a base which is substantially rectangular in cross-section and which is formed with a peripheral flange 11 at its lower end. The base is suitably anchored to the ground surface adjacent a vehicle parking space, as will be explained. The upper end of the base is formed with a cylindrical, internally screw-threaded opening 12 and the lower end of an elongate tubular post 13 is screwed into this opening, whereby said post extends upwardly from the base. A tubular head or housing 14 has its lower end telescoping the upper end of the post 13 and may be suitably secured to said post by a set screw 15 (Figures 3 and 10). The set screw extends through the upper end of the post from the interior thereof and has its end engaging the bore of the tubular head. The upper end of the head or housing 14 is closed by a cap 16 which is threaded into said head. The

top of the cap 16 is spaced from the remainder thereof by a plurality of vertical pins 17, whereby the interior of the cap may be observed from any direction around the head. The specific details of the cap will be hereinafter set forth. An incandescent lamp or bulb 18 is located within the cap and, when illuminated, is visible from any direction.

A coin slot 19 is located in the wall of the head or housing 14 near the upper end thereof, while recessed openings 20 are provided in said housing below the slot. The openings are located diametrically opposite each other and have a magnifying lens 21 covering the same. An indicating dial 22 (Figure 10) is visible through each opening and the dials are formed with a central aperture 23, whereby a coin deposited in the slot 19 may fall between the dials and be retained therebetween so as to be visible through said apertures. Since the recessed openings 20 are located diametrically opposite each other in the housing, it will be manifest that one of said openings may be directed outwardly so as to be visible from the street, which would dispose the other opening in full view of an observer on the sidewalk. The base 10, as well as the post 13, are preferably constructed of non-magnetic material such as brass, while the head or housing may be made of any suitable metal. The exterior of the base, post and head may be painted or enamelled to make the same more attractive.

The device is mounted adjacent the parking space and is usually anchored in the sidewalk contiguous to the curbstone. The disposition of the bulb 18 within the cap, together with the construction of said cap, permits the bulb to be observed from any direction or angle, while the location of the recessed openings 20 is such that the dials 22 are visible from either the street or the sidewalk. It is pointed out that the bulb 18 may be of any desired color when illuminated, it being preferable that this color be red. It is believed that a brief description of the operation of the meter will clarify the purposes and objects and therefore, the particular means employed for performing the functions will be subsequently described.

One of the devices is, of course, mounted adjacent each parking space throughout the length of the street and all of the devices are controlled from a single master control. Since the meters are used only during the daytime as for example, from 7:00 A. M. to 6:00 P. M., the meters would not be in operation during the remainder of the day and night. When the meter is placed in condition for operation through the master control, the bulb 18 is immediately illuminated so that a dim light is visible to the observer. The current to the bulb 18 at this time is passing through a resistance whereby said bulb is not brightly illuminated, but is more or less of a dim glow. This dim light indicates that the meter is in operation but that the parking space governed by such meter is unoccupied and no coin has been inserted into said meter.

When the motorist drives his vehicle into the parking space and properly parks said vehicle therein, a magnetic element, as will be explained, within the base 10 is operated to actuate an electrical switch, whereby the bulb 18 is changed from a constant dim glow to a bright flasher. That is, as soon as the car is properly parked within the space, the bulb 18 begins to flash to indicate to the motorist that his vehicle is in

proper position and that a coin must be inserted into the coin slot 19 to pay for the space.

When the coin is deposited in the coin slot 19, the same falls downwardly between the dials 22 and as it does so it operates a switch which extinguishes the bulb 18 whereby the flashing signal is cut off. The coin is retained between the dials 22 and is clearly visible through the apertures 23 in said dials. At the same time that the bulb 18 was caused to change from a dim glow to a flashing signal, the dials 22 were started in their rotation whereby the time began registering immediately when the vehicle entered the space. This makes it impossible for the motorist to drive into the space and wait five or ten minutes before depositing his coin, and thereby obtain an additional parking period. Throughout the allotted time, the bulb 18 remains extinguished and the dials 22 rotate to record this time. The coin being retained between the dials is clearly visible at all times and an observer may readily note, at a glance, the coin as well as the indication on the dials 22.

A police officer can readily observe the meter from a distance and can immediately determine which parking spaces are unlawfully occupied. If a vehicle is within a particular space and the bulb 18 is flashing, this indicates that the motorist has not deposited his coin. If the space is unoccupied, the bulb 18 will be dimly lighted and in the event that a car is within a space with said bulb dim, then the officer immediately knows that the vehicle is not sufficiently close to the curb and is therefore improperly parked. The use of the illuminated signal which is visible from any direction eliminates the necessity of the officer walking to each meter to determine whether any car is occupying a space without payment.

After the time has expired on the meter, as indicated by the dials 22, the bulb 18 is again illuminated to indicate that the vehicle is parked overtime in the space. The illumination of the bulb at this time is very bright as against the dim glow when the parking space is unoccupied, whereby a difference in the brightness of the light indicates to the observer the condition of the meter. Thus, if a car is within the space and the bulb 18 is dim, this indicates that the car is improperly parked, whereas if the bulb is bright with a car within the parking space, the observer immediately knows that the parking period has expired for that space.

The bulb 18 will remain brightly illuminated and the coin will be retained within the dials 22 until the vehicle is moved from the parking space. Therefore, it is impossible to place another coin within the slot to again actuate the meter until the vehicle within the space has been moved out of said space and another vehicle entered therein. As soon as the vehicle leaves the space, the bulb 18 is returned to a dim glow and at the same time the coin between the dials 22 is dropped from therebetween. Also, the dials are returned to a starting position so as to be ready for the next operation. When the next vehicle drives into the space, the bulb 18 again begins to flash to indicate to that motorist that he is properly parked and that a coin must be inserted. Insertion of the coin by the second motorist will repeat the operation as above described.

The base unit

Referring to Figure 12, it will be seen that the base unit includes the base 10 which is hollow

and which, as has been stated, is substantially rectangular in cross-section. An anchor plate 25 is embedded in the concrete sidewalk 26 adjacent the curbstone and is rigidly fastened thereto by anchor bolts 27. The plate has an upwardly extending tubular stud 28 which projects through an opening in the upset bottom 29 of the base 10. A nut 30 is screwed onto the upper end of the stud and securely fastens the base to the anchor plate.

A metallic conduit or pipe 31 is embedded in the concrete 26 and has its upper end extending through the tubular stud 28 and nut 30 and electrical lead wires A and B are confined within said conduit. The wires lead from a generator G or other suitable source of supply and conduct the electrical current to the electrical apparatus within the device as will be hereinafter explained.

A magnetic element 32 which is substantially U-shaped is mounted to swing within the base 10, being secured to the lower end of a rod 33 which has its upper end extending into the post 13. The extreme upper end of the rod is provided with an opening 34 through which a transverse supporting pin 35 extends, whereby said rod is suspended from the pin. The pin is substantially triangular in cross-section whereby the rod is suspended from one of the knife-like edges of the pin, the mounting being similar to that used in supporting scale beams. Normally, the rod 33 hangs vertically from the pin which places the magnet 32 in the position shown in dotted lines in Figure 12.

The arms 32' or poles of the magnet are directed outwardly toward the street whereby the area of stress or magnetic field between the poles extends beyond the curbstone as indicated by the dotted lines S. When a vehicle is driven into the parking space the magnetic mass of the vehicle enters the area of stress between the poles and the magnet is drawn toward the vehicle into the position shown in full lines in Figure 12, whereby the magnet is swung on the pin 35. The magnet is of such strength that its area of stress extends approximately eighteen inches beyond the curbstone, whereby the vehicle must be parked within eighteen inches of said curb in order to swing the magnet. Of course, this distance may vary and the invention is not to be limited to the particular distance herein specified. The base 10 and post 13 are of non-magnetic material and do not effect the magnet.

It is pointed out that the magnet 32 must have sufficient strength to create the magnetic field within the parking space but yet, due to the fact that it must be mounted within the device, its size must be limited. The usual magnetic material has been found unsuitable for the purpose herein because to obtain the necessary strength the size of the magnet would prevent its use in a parking device of this character. The magnet 32 is constructed of a metal alloy known as "Alnico" and is sold by the General Electric Company of Schenectady, New York. The maximum available energy is higher for "Alnico" than for the usual magnet alloys and occurs at a lower flux density and a higher demagnetizing force and therefore, maximum magnetic force with a minimum size magnet may be obtained through the use of this alloy. However, there may be other magnet alloys which could be used, although they are not generally known. Suffice it to say that so long as sufficient magnetic force

is obtained with a magnet of comparatively small size so as to be insertable within a parking device, the purposes of this invention will be accomplished.

Within the base 10 and between the arms 32' of the magnet, an electrical contact arm 40 is mounted. This arm has one end rigidly fastened to a support 41 while its other end is free to swing. The arm is electrically connected to the lead wire A which conducts electrical current thereto. The free end of the arm 40 is located in the path of an angular actuating member or lug 42 which is attached to the magnet 32, whereby when the magnet is swung by the entrance of a vehicle into the parking space, the contact arm 40 is also swung.

Normally, the arm 40 is in engagement with a switch blade 43 which is also secured to the support 41 and thus when the magnet is in a normal position (dotted lines, Figure 12) an electrical circuit is closed between the arm 40 and blade 43. When the magnet is swung the arm is disengaged from the blade 43 and is moved into engagement with a blade 44 to conduct the current from the wire A to said blade 44. As will be explained, the engagement of the arm and blade 44 closes an electrical circuit which actuates the dials 22 to start rotation thereof, whereby when a vehicle enters the parking space and the magnet is swung the dials begin to operate. When the vehicle leaves the space, the magnet immediately swings to its normal position, permitting the arm 40 to re-engage the blade 43 and this closes a circuit to the clearing apparatus as will be explained, to clear the meter and return the dials to a starting position in readiness for the next operation.

Above the arm 40 and blades 43 and 44, a second contact arm 45 is mounted on a support 46. The free end of this arm is also in the path of the lug 42 on the magnet and is normally in engagement with a switch blade 47. When so engaged an electrical circuit is closed through a resistance (as will be explained) to the bulb 18, whereby said bulb is dimly lighted when the magnet 32 is in a normal position and no vehicle is within the space.

When a vehicle enters the space the magnet swings to move the arm 45 into engagement with the switch blade 48, which closes an electrical circuit to the bulb 18 through a flashing apparatus, whereby the bulb which was dimly lighted flashes on and off. It is noted that the magnet 32 swings the arms 40 and 45 simultaneously whereby the circuits, controlled by the movement of said arms, are broken and completed simultaneously. Since the swinging magnet controls the position of the arms 40 and 45, it might be said that the presence or absence of a vehicle within the space controls said arms and their respective circuits, which will be hereinafter set forth.

The post unit

The tubular post 13 has its lower end threaded into the base and extends upwardly therefrom while its upper end is inserted within and is fastened to the lower end of the head or housing 14. Below the lower end of the head, the upper portion of the post is provided with an elongate rectangular opening or slot 49 which permits access to the interior of the post. The slot is of sufficient size to allow insertion or removal of a suitable coin container or receptacle 50 which is adapted to be supported upon a transverse shelf 51 disposed within the post. The coin con-

tainer has a flared opening in its top to guide the coins falling from within the head into said container. The upper portion of the post is also formed with a vertical slot 52 (Figure 3).

For closing the slot 52 and the opening 49 to prevent unauthorized access to the coin container, an elongate sleeve 53 is slideable vertically on the post and when said sleeve is in a raised position, the upper end of the sleeve engages within an annular recess 54 provided in the lower edge of the head or housing 14. A key-operated tumbler mechanism 55 is mounted within an opening 56 formed in the upper end of the sleeve and said mechanism extends inwardly through the vertical slot 52 into the interior of the post. The tumbler mechanism includes a shaft 57 which is rotatable by a suitable key (not shown) and this shaft has a hook 58 secured to its inner end. When the sleeve 53 is in a raised position, the hook is adapted to engage over the inner end of the screw 15 which fastens the head 14 and post 13 together. The engagement of said hook with the screw locks the sleeve in a raised position from which it cannot be moved until a key (not shown) is utilized to rotate the shaft 57 and disengage said hook from the screw 15. As the sleeve is slid downwardly to uncover the opening 49 the tumbler mechanism 55 moves downwardly in the vertical slot 52. It is pointed out that the wires which lead from the contact arms 40 and 45 and switch blades 43, 44, 47 and 48 may be enclosed in a single sheathing or conduit 59 which extends upwardly through the post and into the head or housing 14 (Figures 10 and 12) to the electrical apparatus within 35 said head.

The coin receiving and dial unit

Above the coin container or receptacle 50 and located within the head or housing 14 is a coin receiving and dial unit 60. This unit is insertable within the housing from the open upper end thereof and has a transverse width which is substantially equal to the internal diameter of the housing, whereby it has a snug fit therein. When in place, the lower end of the unit rests upon the upper end of the post 13 which is located within the lower end of the housing. The unit includes a pair of side plates 61 and 62 between which the coin receiving mechanism is mounted. An electrical bulb receptacle 63 is secured by the upper end of the plate 61 and receives the bulb 18, whereby said bulb is supported within the cap 16.

The side plate 61 (Figures 4, 5 and 9) has a spacer plate 64 secured to its inner surface by screws 65 and this plate is of substantially the same size as the side plate. A circular opening 66 is formed in the inner plate 64 and an enlarged gear 67 is mounted to rotate therein. A concentric opening 68 is provided in the side plate 61 and is smaller in diameter than the opening 66, whereby the peripheral portion of the gear 67 is hidden when observed from the outer side of the plate 61, the remainder of the gear being clearly visible through the opening 68. The central portion of the gear is cut out to form the aperture 23 and this aperture is closed by a glass window 69. The outer portion of the gear surrounding the aperture 23 is visible through the opening 68 in the side plate and this portion is provided with suitable indications or numerals to form the indicating dial 22. The indications on the dial represent minutes or other durations of time and the opening 68 is so 75

located in the plate 61 that when the unit 60 is in position within the head or housing 14, the dial 22 on the gear 67 is clearly visible through one of the sight openings 20 of the housing. A suitable pointer 70 (Figure 4) is fastened to the outer side of the plate 61 and when the dial is in a starting position, the pointer is opposite the zero on said dial.

10 The dial gear 67 is in constant engagement with a smaller gear 71 which is mounted within a recess 72 formed in the inner plate 64. Being in constant mesh with the gear 67, the gear 71 is rotated therewith and is employed for resetting or returning the dial to its starting position.

15 The other side plate 62 of the unit 60 (Figures 7 and 8) is constructed in substantially the same manner as the plate 61, being provided with an inner plate 64' fastened thereto by bolts 65'. The plate 64' has an opening 66' wherein a dial gear 67' is rotatably confined. The side plate 62 has an opening 68' concentric to the opening 66' in the inner plate and the second dial 22 is formed on the outer surface of the gear 67'. This latter gear has the aperture 23 therein, through which the coin inserted into the device, is visible. The inner plate 64' has a recess 72' above the opening 66' and a smaller gear 71' which is in constant mesh with the gear 67', is rotatably confined in said recess. The gear 71' is connected with the gear 71 by a stub shaft 73 whereby said gears are simultaneously rotatable. The plates 61 and 62, as well as the inner plates 64 and 64', are of the same size and the openings and recesses are disposed alike in each, whereby when the plates are secured to each other, the gears 67 and 67' and the gears 71 and 71' are lined with each other.

20 Spacer members 75, 76 and 77 are interposed between the inner plates 64 and 64' and serve to space said plates from each other when the unit is assembled. The bolts 65 pass through the plates 61, 62, 64 and 64' and through the spacing members to fasten the parts together, and the width of said members is substantially equal to the width of the coin which operates the device. When the parts are so assembled the shaft 73 which connects the gears 71 and 71' extends through a recess or cut out 78 formed in the upper end of the spacer member 75. A flat spring 79 surrounds the shaft within this recess and has one end secured thereto with its other end fastened to a pin 79', whereby said spring constantly urges the gears 71 and 71', as well as the dial gears 67 and 67' to rotate in a direction which will return said dial gears to a starting position, as will be explained.

25 For imparting a rotation to the dial gears 67 and 67' so that the dials 22 thereon indicate the lapse of time, an actuating magnetic coil 80 is mounted on the outer surface of the plate 62 at the lower end thereof (Figure 8). An arm 81 has its lower end pivotally mounted on the bracket 80' and the free or upper end of said arm is adapted to swing inwardly toward the coil when the coil is energized. A coiled spring 82 is secured to the lower end of the arm and constantly exerts its tension to urge the upper end of the arm outwardly from the coil, the opposite end of the spring being attached to a fixed lug depending from the bracket. The outward swinging of the arm is limited by a set screw 83 which is located in the path of said arm.

30 The extreme upper end of the arm 81 has one end of a laterally extending actuating bar 84

secured thereto and the outer end of said bar is bent inwardly and extends through a rectangular opening 85 formed in the plates 62 and 64', whereby said inner end is located adjacent the teeth of the dial gear 67'. The actuating bar is made of flexible material such as spring metal, whereby its inner end is held in constant engagement with the teeth of the gear 67'. When the coil 80 is energized the arm 81 is attracted thereto and the actuating bar is moved to engage the next tooth of the gear 67'. As said coil is de-energized, the spring returns the arm 81 and bar 84 to its original position, whereby rotation is imparted to the gear 67'. Rotation of this gear rotates the small gears 71 and 71' which rotate the other dial gear 67. The flat spring 79 which surrounds the shaft 73 of the small gears is so arranged that as the actuating bar rotates the gears, the spring is wound and acts to resist movement of the gears by said bar, tending at all times to rotate the gears in an opposite direction. The coil 80 which operates the actuating bar is energized periodically by an electrical time impulse mechanism or synchronous electric motor 200 (Figure 11) whereby a step by step actuation of the dial gears is accomplished. When the magnetic element 32 is in the position shown in full lines in Figure 12 with a vehicle within the parking space, the contact arm 40 is engaging the switch blade 44 to close the electrical circuit to said coil. Therefore, unless a vehicle is within the space, the coil 80 cannot be energized.

For holding the gear 67' from reverse rotation by the resetting gears 71 and 71' while the actuating bar 84 is moving to engage the next gear tooth, a retaining pawl 86 which is constructed of flexible material, has one end secured to the outer surface of the plate 62, while its free end is arranged to engage the teeth of the gear 67'. Obviously, the ratchet bar normally prevents reverse rotation of the gears 67 and 67' and must be moved out of engagement with the teeth of the gear 67' before such reverse rotation can occur.

For limiting the rotation of the dial gears 67 and 67' in either direction, the gear 67 is provided with an outwardly extending pin 87 (Figure 8) which extends through the opening 68' in the plate 62. The pin is mounted near the periphery of the gear 67' and is shown as located opposite the zero indication on the dial 22. The position of said pin is subject to variation and it may be disposed in any one of a number of openings 88 provided in the gear 67'. It is pointed out that the position of the pin controls the length of time which the dials will rotate and therefore, controls the parking period as registered by said dials. When the dials are inactive and the device is not registering the parking period, the pin is in engagement with an inwardly directed lug 89 provided on the lower end of a T-shaped switch member 90. As clearly shown in Figure 8, the lug is disposed above a pointer 70' secured to the plate 62 and similar to the pointer 70.

The switch member 90 includes a vertical leg 91 and a pair of laterally extending arms 92 and 93 and is pivotally mounted on a pin 94 at the upper end of the plate 62. The member is balanced so that when the pin 87 on the dial 22 is not in engagement therewith, the leg 91 is suspended vertically while the arms 92 and 93 are extending horizontally or at right angles to the leg. When the dials are inactive, however, the pin is in the position shown in Figure 8 and the member is

swung as shown. In such position the outer end of the arm 92 is engaging a switch blade 95 and is holding said blade in engagement with a switch blade 96 whereby an electrical circuit between said blades is closed. The blades 95 and 96 are constructed of spring metal and are mounted on an insulating block 97 secured to the plate 62. The disposition and flexibility of the blades are such that when the pin 87 disengages the lug 89 and the switch member 90 returns to a normal position with the arm 92 horizontal, the inherent resiliency of the lower blade holds said blades in engagement, said lower blade following the upper blade in its movement. It is only when the member 90 is swung in an opposite direction by the pin 87 engaging the opposite side of the lug 89 that the blades 95 and 96 are disengaged from each other, such disengagement being affected by the blade 95 moving upwardly, due to its flexibility, away from the blade 96, which latter blade remains in a horizontal position. This engagement of the pin 87 with the lug 89 on the side opposite that shown in Figure 8 occurs when the dials have completed their movement and it is at this time that the blades 95 and 96 are disengaged to break the circuit therebetween. The blades are connected in the time impulse coil 80, as will be explained, and when separated break the circuit to said coil to prevent further energization thereof, which stops the rotation of the dials 22.

The other arm 93 of the switch member 90 has its outer end secured to a switch blade 98 which is carried by an insulating block 99 secured to the plate 62. This blade is arranged to engage a contact arm 100 which is also carried by said block whereby an electrical circuit is completed to a release coil 102 which is mounted at the lower end of the plate 61 (Figure 4), as will be explained. When the switch member is in the position shown in Figure 8, the blade 98 is disengaged from the blade 100 but when the pin 87 moves away from the lug 89 of the switch member, said member swings to a normal position with its leg 91 vertical and its arms 92 and 93 horizontal. In such position, the blades 98 and 100 are engaged.

A third switch blade 103 is mounted on the block 99 below the blade 100 and is adapted to be engaged by the blade 100 when the switch member is swung to its opposite position by the engagement of the pin 87 with the lug 89 on the side opposite that shown in Figure 8. This engagement of these switch blades closes a direct circuit to the bulb 18 to brightly illuminate said bulb and manifestly, the bright illumination of said bulb occurs when the travel of the dials is completed and the parking period has expired.

From the foregoing, it will be seen that the dials 22 are rotated by the actuating bar 84, which is operated by the time impulse coil. As the dials begin their movement, the pin 87 leaves the lug 89 (Figure 8) to permit the switch member 90 to swing to a normal position. At such time the blades 95 and 96 which control the circuit to the impulse coil 80 remain in engagement, and the blades 98 and 100 move into engagement. These latter blades are connected in the circuit to the release coil 102 but cannot alone energize said coil because the contact arm 40 in the base 10 must be engaged with the arm 45 before said coil is operated and when the dials are rotated said arm 40 is engaging the contact 44 to close the circuit to the coil. Therefore, it is impossible to energize both the coils 80 and 102 simultaneously, as will be hereinafter explained.

As the dials 22 are rotated they, of course, in-

dicate the lapse of the parking time and when the period has expired, the pin 87 engages the lug 89 of the switch on the side opposite that shown in Figure 8. This swings the member from the normal position in which it has been hanging or suspended to a position which raises the arm 92 and lowers the arm 93. Raising of the arm 92 permits a disengagement of the blades 95 and 96 which breaks the circuit to the coil 80 to prevent further energization thereof, whereby rotation of the dials is immediately halted. At the same time, the lowering of the arm 93 engages the blades 100 and 103 which completes a direct circuit to the bulb 18 to brightly illuminate the same. The blades 98 and 100, of course, remain in engagement but no current is passing therethrough to the release coil 102 because, as explained, said circuit is broken between the contact arm 40 and blade 43 in the base.

The parts remain in this position until the vehicle is removed from the parking space and as soon as this is done the magnet 32 in the base returns to a normal position (dotted lines Figure 12) which engages the contact arm 40 with the blade 43, thereby completing the circuit to the release coil 102 whereby the coil is energized.

The coil 102 is mounted in a bracket 104 secured to the plate 61 and a laterally extending arm 105 overlies the coil. One end of the arm 105 is secured to one end of a shaft 106 which extends through the plates 61, 62, 64 and 64', and when the coil is energized the arm is attracted thereto to impart a rotation to the shaft. For returning the shaft and arm 105 to their original positions after the coil 102 is deenergized, a spring 107 is confined between the inner end of the arm and a lug 104' in the bracket 104 and urges the arm upwardly. The shaft 106 extends through the plates and has its opposite end projecting from the plate 62 as shown in Figure 8, said projecting end being located above the set screw 83. An angular release member 108 is fastened on the shaft 106 and overlies the actuating bar 84 and outer end of the ratchet bar 86. When the shaft 106 is rotated by the energization of the release coil 102, the angular member 108 is moved downwardly to engage the actuating bar 84 and ratchet bar 86 to disengage the same from the teeth of the gear 67'. Such disengagement of the bars 84 and 86 permits the flat spring 79 on the stub shaft 73 of the gears 71 and 71' to rotate said gears and thereby impart a reverse rotation to the gears 67 and 67'. Such reverse rotation continues until the pin 87 on the dial gear 67' strikes the lug 89 swinging the switch member 90 to the position shown in Figure 8. Such swinging of the member separates the blades 98 and 100 to break the circuit to the coil 102, which allows the spring 107 to return the shaft 106 to its original position to swing the angular release member 108 upwardly out of engagement with the ratchet and actuating bars 86 and 84 respectively. Thus, it is manifest that when the vehicle leaves the parking space the release coil 102 is energized to return the dials 22 to a starting position in readiness for the next operation.

The spacer members 75, 76 and 77, which are disposed between the side plates, form the coin receiving chute and passage and are clearly shown in Figure 6. The member 75 has a general angular shape and is provided with an inclined edge 110 which forms the upper side of an inclined coin chute 111 which leads from the coin slot 19 in the head or housing 14. The lower side of the

chute is formed by the inclined upper edge 112 of the member 77. The inner extremity of this edge is extended to provide a projecting point 112' which is disposed adjacent the apertures 23 in the dials 22. A coin which is inserted within the chute will roll or fall downwardly therein and will strike the lower end of a vertical bar or lever 113 which has its upper end disposed within a recess or slot 114 formed in the member 75. The upper end of the lever is secured on a rotatable pin 115 which extends outwardly through the side plate 61 (Figure 4). Normally, the lever is in the position shown in Figure 6 with its lower end in the path of the coin, but when said coin strikes the same, the lever is swung to the position shown in dotted lines thereby rotating the shaft 115.

The outer end of the shaft has an arm 116 secured thereto and rotation of the shaft swings said arm. The free end of the arm is disposed between two switch blades 117 and 118 (Figure 4) which are secured to an insulating block 119. A contact arm 120 is located between the blades and is adapted to be engaged by one or the other thereof. When the lever 113 is in a normal position (full lines, Figure 6) the arm 116 is raised, with the blade 118 engaging the arm 120. The blade 118 is connected in the circuit of the bulb 18 and co-acts with the contact arm 45 and blade 48 to impart a flashing illumination to said bulb. When a coin is inserted, the lever 113 is swung which swings the arm 116 to separate the blade 118 and arm 120 and engage the blade 117 with the arm 120. The blade 117 is connected in the circuit of the release coil 102 and co-acts with the contact arm 40 and blade 43 in the base 10 to energize said release coil.

The spacer member 76 has an extension 76' which co-acts with the vertical inner edge of the member 77 to form a coin passage 121 through the unit. The upper end of the extension terminates below the lower end of the lever 113 and an angular retaining pawl 122 is pivotally mounted adjacent this upper end. The pawl has an extending lug 123 which overhangs the extension and when said pawl is in the position shown in full lines in Figure 6, the distance between the lug and the point 112' at the lower end of the coin chute is slightly less than the diameter of the coin. Thus, when a coin is inserted in the chute, it strikes the lower end of the lever 113 to swing the same and is then caught between the lug 123 on the pawl and the point 112' which positions said coin between the gears 67 and 67' in alignment with the apertures 23, whereby said coin is visible through said apertures and through the recessed openings 20 in the head or housing 14.

The coin is retained in this position until the dials 22 have completed their movement and the parking period has expired and is released only when the coil 102 is energized by the removal of the vehicle from the parking place. As has been previously explained, the release coil 102 rotates the shaft 106, which extends through the plates and rotation of the shaft disengages the actuating bar 84 and ratchet bar 86 to permit the dials to be reset. For releasing the coin from its position between the gears, an arm 124 is secured on the shaft 106 and is located between the inner plates 64 and 64' below the pawl 122. The arm is adapted to engage the depending leg 125 of the pawl 122 and when the shaft 106 is rotated by the energization of the release coil 102, the arm 124 is swung which swings the lug 123 of the pawl upwardly, whereby the coin is permitted to fall through the coin passage 121 and downwardly

into the coin container 50. Thus, it will be seen that movement of the vehicle from the parking space energizes the release coil 102 and such energization of the coil, not only permits resetting of the dials 22 to a starting position, but also releases the coin from between said dials. It is pointed out that another coin which may be inserted before the previously deposited coin has been released cannot operate the mechanism but will merely hang in the coin chute 111 above the coin held in alignment with the apertures. Therefore, the vehicle must be removed from the parking space to clear the device before it can again be actuated.

The operation and wiring diagram

When the parking space is unoccupied, the magnet 32 is in the position shown in dotted lines in Figure 12 and the various switches are in the position shown in full lines in the other figures. The position of the switches is also shown in full lines in the wiring diagram in Figure 11. At this time the contact arm 40 within the base 10 is engaging the switch blade 43 and the current from the synchronous motor 200 is flowing through the wire A and to the blade 43. The motor or time impulse mechanism 200 forms no part of the present invention and, as shown in Figure 11, is of the usual construction. This mechanism includes a cam 200a having a pivoted arm 200b riding on its periphery. The arm 200b is pivoted on a second arm 200c and a spring 200d is secured to the arm 200b, holding it in engagement with the cam 200a. The outer end of the arm 200b is adjacent a switch blade 201 which is arranged to engage a blade 202 to close a circuit to a relay 203 to energize the latter. The relay 203 controls a switch arm 204 which closes the circuit to the operating coil 80 of the meter.

The cam is carried by the constantly rotating shaft and, as the arm 200b drops off the offset in the cam 200a, the switch blades 201 and 202 are engaged to close a circuit to the relay 203 and thereby energize the operating coil 80. When the second arm 200c drops off the offset in the cam, the end of the arm 200b is disengaged from the blade 201 to break the circuit. As the cam rotates, the making and breaking of the circuit to the coil 80 is continued, resulting in a step-by-step actuation of the dials.

Upon each electrical impulse, the current flowing through the wire A also flows to the blade 43. From the blade the current passes through a wire 102a to the release coil 102, through said release coil and then through a wire 102b which connects to the switch blades 98 and 117. The switch blade 98 is disengaged from the contact arm 100 which contact arm is connected to a ground wire 100a. It is noted that the switch blade 98 is held in its disengaged position by the T-shaped switch member 90, as is clearly shown in Figure 8. The switch blade 117 which is also connected to the wire 102b leading from the release coil is disengaged from the contact arm 120 by the arm 116, which latter arm is controlled by the lever 113 within the coin chamber. The contact arm 120 is also connected to the ground wire 100a and therefore the circuit to the release coil is broken when a vehicle is not within the space.

The position of the magnet 32 (dotted lines in Figure 12) also permits the engagement of the contact arm 45 with the switch blade 47. The current from the motor 200 flows through the wire A and then through a wire 18a which is connected to one side of the bulb 18. The other side

of the bulb 18 is connected through a wire 18b with the contact arm 45, whereby the current flows to the switch blade 47. From the blade 47 the current is conducted through a wire 47a which is connected to the ground wire 100a to complete the circuit through the bulb 18. A suitable resistance R is connected in the wire 47a whereby the current passes through this resistance and causes the bulb to be dimly illuminated at this time. Thus, when the device is not operating and a vehicle is not occupying the space adjacent thereto, the current to the bulb 18 is completed through the resistance R whereby a dim light is visible to the observer. At this time the circuit to the release coil 102 is broken because of the position of the switch blades 98 and 117. Also, the circuit to the time impulse coil 80 which actuates the dials 22 is broken since the contact arm 40 is disengaged from the contact blade 44.

When a vehicle enters the parking space, the magnet 32 is attracted toward said vehicle, whereby it is moved to the position shown in full lines in Figure 12. Such movement of the magnet disengages the contact arm 40 from the blade 43, whereby the circuit to the release coil is broken at this point. It is noted that the circuit to said release coil cannot be closed until the vehicle leaves the parking space and returns the magnet 32 to its original normal position and, therefore, so long as the car remains in the space, the release coil cannot be energized regardless of the position of the switch blades 98 and 117 connected in the release coil circuit.

As the magnet is swung by the entrance of the vehicle, the contact arm 40 is swung to engage the blade 44 whereby the current from the motor 200 may flow through the supply wire A through the contact arm 40 and to the blade 44. From the blade 44 the current flows through a wire 80a to the switch blade 96 which is mounted on the side plate 62 of the dial unit. The switch blade is in engagement with the blade 95 which is connected by a wire 80b to one side of the time impulse coil 80. The other side of the coil 80 is connected to the supply wire B whereby the circuit to the motor is complete. As soon as the coil 80 is energized by the engagement of the arm 40 with the blade 44, the dials 22 begin their rotation through the medium of the actuating bar 84 operated by the coil 80. As the dials begin their movement, the pin 87 moves away from the lug 89 of the switch member 90, whereby said member is permitted to move to a normal position with its vertical leg 90 suspended from the pin 94 and the arms 92 and 93 extending horizontally of the side plate 62. The swinging of the switch member 90 does not disengage the blades 95 and 96 and thereby hold the circuit to the coil 80 complete throughout the rotation of the dials 22. However, when the switch member 90 is swung the switch blade 98 is engaged with the contact arm 100 whereby the circuit to the coil 102 is made ready for completion whenever the contact arm 40 is re-engaged with the switch blade 43.

The swinging of the magnet 32 by the entrance of the vehicle not only closes the circuit to the actuating coil 80, but also disengages the contact arm 45 from the switch blade 47, swinging said arm so as to engage it with the switch blade 48. The switch blade 48 is connected by a wire 48a with a suitable flashing mechanism F. The other side of said flasher is connected by a wire 48b with the switch blade 118, which blade is mounted on the side plate 61 of the dial unit and

is controlled in its movement by the arm 116 which is actuated by the lever 113 within the coin chamber. The blade 118 is engaging the contact arm 120 which is connected to the common ground wire 100a and therefore until a coin is inserted in the coin chute to swing the lever 113, the circuit between the blade 118 and arm 120 is complete.

Therefore, it will be seen that when the magnet 32 is swung to engage the contact arm 45 with the switch blade 48, the circuit to the bulb 18 is through the supply wire A, wire 18a, bulb 18, wire 18b, contact arm 45, switch blade 48, flasher F, switch blade 118 and finally through the contact arm 120 to the ground side of the circuit. A completion of the electrical circuit through the flasher F causes the bulb 18 to change from a dim glow to a constant flashing. This indicates to the motorist that his vehicle is properly parked within the parking space and a coin must be inserted to pay for the parking period. The time as indicated by the dials 22 begins to register, however, as soon as the vehicle enters the space for as soon as the arm 40 contacts the blade 44, the circuit to the time impulse coil 80 is complete and the dials begin their rotation at this time.

When a coin is inserted in the coin slot 19, it will fall downwardly through the coin chute 111 and will strike the lower end of the pivoted lever 113 whereby said lever will rotate the shaft 115 and will swing the arm 116 downwardly (Figure 4). This swinging of the arm 116 disengages the switch blade 118 from the contact arm 120 whereby the bulb circuit through the flasher F is immediately broken. Breaking of this circuit extinguishes the bulb 18. The bulb remains in this condition until the parking period has expired as will be presently explained. At the same time that the arm 116 disengages the blade 118 from its contact arm 120, it engages the switch blade 117 with said contact arm 120 so as to close the circuit from the wire 102b to the ground 100a. However, the release coil 102 which is connected to the wire 102b is not actuated at this time because, as has been hereinbefore pointed out, the contact arm 40 is disengaged from the switch blade 43 which is connected to the other side of the release coil 102.

From the above, it will be seen that insertion of the coin into the coin chute 111 will swing the lever 113 within the dial unit 60, whereby the arm 116 will be swung to extinguish the bulb 18. The parts remain in this position and the dials continue their rotation to indicate or record the parking period. In the event that the vehicle is removed from the parking space before the dials 22 have completed their movement, it will be manifest that such removal of the vehicle will return the magnet 32 to its original or normal position as indicated by the dotted lines in Figure 12. In such case, the contact arm 40 within the base 10 will be disengaged from the blade 44 and re-engaged with the blade 43. The engagement of the arm 40 with the blade 43 will close the electrical circuit to the release coil 102, the current flowing from the supply wire A, through the arm 40, blade 43, wire 102a, then through the coil, wire 102b, switch blade 98 and contact arm 100 to the common ground 100a, whereby the circuit to the coil is complete. It is pointed out that the blade 98 is in engagement with the contact arm 100 (Figure 8) since the switch member 90 is in a normal position with its arms 92 and 93 extending horizontally of the side plate 62.

Therefore, if the vehicle is removed from the space, the release coil 102 is energized, whereby the shaft 106 is rotated through the medium of the arm 105 which is attracted to the coil by the energization thereof. Rotation of the shaft 106 swings the release member 108 to disengage the actuating bar 84 and the ratchet bar 86 from the teeth of the dial gear 67', whereby the flat spring 79 surrounding the stub shaft 73 of the resetting gears 71 and 71' is permitted to return the dials to a starting position. It is pointed out that when the circuit is completed to the release coil 102, the disengagement of the contact arm 40 with the contact 44 breaks the circuit to the time impulse or actuating coil 80.

The rotation of the shaft 106 by the release coil 102 also swings the arm 124 which is located between the plates of the dial unit 60 (Figure 6). The swinging of this arm causes the arm 122 to swing upwardly, whereby the coin which is retained in alignment with the apertures 23 is permitted to fall downwardly through the coin passage 121. Thus, at the same time that the dials 22 are returned to their starting position, the coin is released from its position between the dials. As the dials 22 return to a starting position, the pin 87 on the dial gear 67' strikes the lug 89 of the switch member 90 to return the same to the position shown in Figure 8. This disengages the blade 98 from the contact arm 100 whereby the circuit to the release coil is again broken. At the same time, the release of the coin from within the dial unit permits the lever 113 within said unit to swing to its normal position, whereby the arm 116 is returned to the position shown in Figure 4, whereby the switch blade 118 is re-engaged with the contact arm 120.

The return of the magnet 32 to its normal position by the removal of the vehicle not only closes the contact to the release coil as explained, but also disengages the switch arm 45 from the contact blade 48 and engages said arm with the blade 47. Such engagement of the arm 45 with the blade 47 again closes the circuit to the bulb 18 through the resistance R whereby said light bulb is again dimly lighted to indicate that the parking space is unoccupied.

Assuming that the vehicle remains in the parking space throughout the parking period, it will be seen that the dials continue their rotation until such time as the pin 87 on the dial gear 67' strikes the lug 89 on the side opposite that shown in Figure 8. When this occurs the switch member 90 is swung completely over to its opposite position, whereby the arm 92 of said switch member is raised, while the arm 93 is lowered. The raising of the arm 92 disengages the switch blades 95 and 96, whereby the circuit to the time impulse coil 80 is broken. The breaking of this circuit causes the dials 22 to immediately stop in their rotation. At the same time that the blades 95 and 96 are separated, the arm 93 has moved downwardly a sufficient distance to engage the blade 100 with the blade 103, whereby a circuit is closed therebetween. By referring to the diagram, Figure 11, it will be evident that when the arm 100 and blade 103 are engaged the electrical current is flowing from the motor 200 through the supply line A, wire 18a, through the bulb 18 and then through a wire 103a which is connected to the blade 103. The current flows through the blade 103 and arm 100 and then to the common ground 100a, whereby a direct circuit through the bulb is completed. This direct circuit causes the

bulb to be brightly illuminated, which indicates that the parking period has expired.

After the expiration of the parking period, the parts remain in this position until such time as the vehicle is removed from the parking space. The removal of the vehicle will cause the magnet 32 to return to its normal position (dotted lines, Figure 12) which causes the contact arms 40 and 45 to disengage the switch blades 44 and 48 respectively and to reengage the switch blades 43 and 47 respectively. Such movement of the contact arms 40 and 45 causes the release coil 102 to be energized as has been explained, which brings about a return of the dials 22 to their normal or starting position which is that shown in Figure 8. Also the circuit to the bulb 18 is again directed through the arm 45 and the switch blade 47 and through the resistance R whereby the bright light is changed to a dim glow upon the removal of the vehicle. At the same time that the dials are returned to a starting position, the coin is released from its position in alignment with the apertures 23 so as to clear the coin chute and passage. Therefore, it will be seen that after a parking period has expired it is impossible to insert another coin to operate the device until the vehicle has been removed from the parking space.

For electrically disconnecting all of the meters operated from the lead wires A and B, a master switch 300, which may be manually operated, is connected in the wire B adjacent the time impulse mechanism 200 and, obviously, when this switch is open, the circuit through wires A and B is open. To individually cut out any meter, a manually operated switch 300a is connected in the wire, preferably adjacent the operating coil. These switches are optional and may or may not be employed, as desired.

In some instances, the parking spaces on the street are not arranged in parallel relation to the curbstone and, in such case, it might be difficult to bring the vehicle sufficiently close to the base 10 to affect movement of the magnet 32. This would be particularly true where vehicles must be parked at a 45 degree angle with relation to the street curbing.

In Figure 13, a modified form of magnetic element for use in the above instances is shown. This form includes a housing 130 of a non-magnetic material which is buried or embedded within the earth or pavement beneath the parking space. A magnet 32' is located within one end of the housing and has its poles directed upwardly. The magnet is secured to one end of a rod 131 which has a counter-balancing weight 132 secured to its other end. The rod 131 is mounted on a triangular shaped pin or bar 133 which is similar to the pin 35. With such arrangement, it will be evident that the magnet is balanced within the housing and when a vehicle passes thereover, the magnetic mass of said vehicle will attract the magnet 32' whereby the rod 131 is swung. The upward movement of the magnet 32' causes the weight 132 to be moved downwardly. This weight carries a suitable actuating bar 134 which is adapted to engage the contact arms 45 and 40 which are located within the lower end of the housing 130. The operation of the remaining parts of the device is exactly the same as has been described and the arrangement shown in Figure 13 is merely another form of mounting the magnetic element 32.

What I claim and desire to secure by Letters Patent is:

1. A coin receiving parking device including, a

housing, timing mechanism within the housing, actuating means for said mechanism, a single electrically operated lamp carried by the housing and visible from the exterior thereof, means for illuminating the lamp in different degrees, means within the housing actuated by the entrance of a vehicle into the parking space adjacent the housing for controlling the operation of the time mechanism actuating means and also for controlling the operation of the lamp illuminating means to change the degree of illumination of said lamp, and means actuated by the insertion of a coin for actuating the illuminating means to de-energize the lamp to extinguish the same.

15 2. A coin receiving parking device including, a housing, timing mechanism within the housing, actuating means for said mechanism, a single electrically operated lamp carried by the housing and visible from the exterior thereof, means for illuminating the lamp in different degrees, means within the housing actuated by the entrance of a vehicle into the parking space adjacent the housing for controlling the operation of the time mechanism actuating means and also for controlling the operation of the lamp illuminating means to change the degree of illumination of said lamp, means actuated by the insertion of a coin for actuating the illuminating means to de-energize the lamp to extinguish the same, means within the housing operated by the timing mechanism for halting the operation of said mechanism, and means also actuated by said timing mechanism for again operating the illuminating means to re-energize the lamp when the parking period has expired.

20 3. A coin receiving parking device including, a housing, timing mechanism within the housing, actuating means for said mechanism, a single electrically operated lamp carried by the housing and visible from the exterior thereof, means for illuminating the lamp in different degrees, means within the housing actuated by the entrance of a vehicle into the parking space adjacent the housing for controlling the operation of the time mechanism actuating means and also for controlling the operation of the lamp illuminating means to change the degree of illumination of said lamp, means actuated by the insertion of a coin for actuating the illuminating means to de-energize the lamp to extinguish the same, means within the housing operated by the timing mechanism for halting the operation of said mechanism, means also actuated by said timing mechanism for again operating the illuminating means to re-energize the lamp when the parking period has expired, and means actuated upon the removal of the vehicle from the parking space for returning the timing mechanism to its starting position.

25 4. A coin receiving parking device including, a housing, a timing mechanism within the housing, an electrically operated signal carried by the housing and visible from any direction exteriorly of the housing, illuminating means for the signal, means for operating said illuminating means to dimly illuminate the signal when a vehicle is not parked within the parking space adjacent the housing, means within the housing and actuated by the entrance of a vehicle into the parking space for operating the timing mechanism, said means also actuating the illuminating means for imparting a flashing illumination to the signal to indicate that the vehicle is properly parked, and means actuated by the insertion of a coin into the device for extinguishing the signal.

5. A coin receiving parking device including, a housing, a timing mechanism within the housing, an electrically operated signal carried by the housing and visible from any direction exteriorly of the housing, illuminating means for the signal, means for operating said illuminating means to dimly illuminate the signal when a vehicle is not parked within the parking space adjacent the housing, means within the housing and actuated by the entrance of a vehicle into the parking space for operating the timing mechanism, said means also actuating the illuminating means for imparting a flashing illumination to the signal to indicate that the vehicle is properly parked, means actuated by the insertion of a coin into the device for extinguishing the signal, and means for brightly illuminating said signal when the parking period as indicated by the timing mechanism has expired to indicate expiration of the parking period.

6. A coin receiving parking device including, a housing, a timing mechanism within the housing, an electrically operated signal carried by the housing and visible from any direction exteriorly of the housing, illuminating means for the signal, means for operating said illuminating means to dimly illuminate the signal when a vehicle is not parked within the parking space adjacent the housing, means within the housing and actuated by the entrance of a vehicle into the parking space for operating the timing mechanism, said means also actuating the illuminating means for imparting a flashing illumination to the signal to indicate that the vehicle is properly parked, means actuated by the insertion of a coin into the device for extinguishing the signal, and means for brightly illuminating said signal when the parking period as indicated by the timing mechanism has expired to indicate the expiration of the parking period, and means actuated upon the removal of the vehicle from the space for extinguishing the bright illumination of the signal, thereby permitting said signal to be again dimly lighted to indicate that the space is unoccupied.

7. A coin receiving parking device including, a housing, a timing mechanism within the housing, an electrically operated signal carried by the housing and visible from any direction exteriorly of the housing, illuminating means for the signal, means for operating said illuminating means to dimly illuminate the signal when a vehicle is not parked within the parking space adjacent the housing, means within the housing and actuated by the entrance of a vehicle into the parking space for operating the timing mechanism, said means also actuating the illuminating means for imparting a flashing illumination to the signal to indicate that the vehicle is properly parked, means actuated by the insertion of a coin into the device for extinguishing the signal, means operated by the timing mechanism for halting the operation thereof, means also operated by the timing mechanism for brightly illuminating the signal when the parking period as indicated by said dials has expired, means actuated upon the removal of the vehicle from the space for extinguishing the bright illumination of the signal, thereby permitting the signal to again be dimly illuminated to indicate that the space is unoccupied, and means also actuated upon removal of the vehicle for returning the timing mechanism to a starting position.

8. A coin receiving parking device including, a housing, a single electrically operated lamp

5 mounted in the housing and visible from all directions exteriorly of said housing, means for lighting said lamp in a particular manner when no vehicle is parked in the parking space adjacent the housing, means within the housing and actuated by the entrance of a vehicle into the parking space for changing the illumination of the lamp, means actuated by the insertion of a coin into the device for extinguishing said lamp, and means again illuminating the lamp in a manner different from the previous illumination thereof when the parking period has expired.

9. A coin receiving parking device including, a housing, a single electrically operated lamp mounted in the housing and visible from all directions exteriorly of said housing, means for lighting said lamp in a particular manner when no vehicle is parked in the parking space adjacent the housing, means within the housing and actuated by the entrance of a vehicle into the parking space for changing the illumination of the lamp, means actuated by the insertion of a coin into the device for extinguishing said lamp, means again illuminating the lamp in a manner different from the previous illumination thereof when the parking period has expired, and means actuated by the removal of the vehicle from the parking space for again illuminating the lamp in the first mentioned manner.

10. A parking device including, a housing having aligned openings in opposite sides thereof, rotatable time indicating dials in said housing and visible through said openings, said dials being spaced from each other and having apertures therein, a coin chute in the housing leading from the exterior of the housing between the dials, and means for retaining the coin in said chute in alignment with the apertures in said dials, whereby the coin and dials are visible through the sight openings in the housing.

11. A parking device including, a housing having aligned sight openings in opposite sides thereof, rotatable time indicating dials in said housing and visible through said openings, said dials being spaced from each other and having apertures therein, a coin chute in the housing leading from the exterior of the housing between the dials, means for retaining the coin in said chute in alignment with the apertures in said dials, whereby the coin and dials are visible through the sight openings in the housing, means for imparting rotation to the dials, means within the housing actuated by the entrance of a vehicle into the parking space adjacent the housing for operating the rotating means to impart rotation to the dials, means for returning the dials to a starting position, and means for releasing the coin from its position in alignment with the apertures in the dials, this latter means being actuated upon removal of the vehicle from the parking space.

12. A parking device including, a housing having aligned sight openings in opposite sides thereof, rotatable time indicating dials in said housing and visible through said openings, said dials being spaced from each other and having apertures therein, a coin chute in the housing leading from the exterior of the housing between the dials, means for retaining the coin in said chute in alignment with the apertures in said dials, whereby the coin and dials are visible through the sight openings in the housing, an electrically operated signal carried by the housing and visible from the exterior of said housing, means for controlling the illumination of the signal, means

within the housing actuated by the entrance of a vehicle into the parking space adjacent the housing for rotating the dials and for actuating the control means for the signal to illuminate the same, and means actuated by the insertion of the coin into the chute for extinguishing said signal.

13. A parking device including, a housing having alined sight openings in opposite sides thereof, rotatable time indicating dials in said housing and visible through said openings, said dials being spaced from each other and having apertures therein, a coin chute in the housing leading from the exterior of the housing between the dials, means for retaining the coin in said chute in alinement with the apertures in said dials, whereby the coin and dials are visible through the sight openings in the housing, an electrically operated signal carried by the housing and visible from the exterior of said housing, means for controlling the illumination of the signal, means within the housing actuated by the entrance of a vehicle into the parking space adjacent the housing for rotating the dials and for actuating the control means for the signal to illuminate the same, means actuated by the insertion of the coin into the chute for extinguishing said signal, means within the housing actuated upon the removal of the vehicle from said space for returning the dials to a starting position, and means also actuated upon removal of the vehicle from said space for releasing the coin from its position in alinement with the apertures in the dials.

14. A coin receiving parking device including, a housing having an opening therein, a time indicating element within the housing and visible through the opening and having an aperture therein, a coin chute within the housing leading past the aperture in the time indicating element, and means for retaining a coin in alinement with said aperture whereby both the coin and element are visible through the opening.

15. A coin receiving parking device including, a housing having an opening therein, a time indicating element within the housing and visible through the opening and having an aperture therein, a coin chute within the housing leading past the aperture in the time indicating element, means for retaining a coin in alinement with said aperture whereby both the coin and element are visible through the opening, means within the housing and actuated by the entrance of a vehicle into the parking space adjacent the housing for operating the time indicating element, means for returning said element to a starting position, and means for releasing the coin from its position in alinement with the aperture in said element, both last named means being operated when the vehicle is removed from the parking space.

16. A coin receiving parking device including, a housing having alined openings therein, rotatable time indicating dials within the housing and visible through said openings, each dial having an aperture therein which apertures are aligned, a coin chute leading past the apertures in the dials, means for retaining a coin in said chute in alinement with said apertures whereby the coin and dials are visible through the openings in the housing, an electrically operated signal carried by the housing, means for controlling the illumination of the signal means wholly within the housing actuated by the entrance of a vehicle into the parking space adjacent the housing for operating the dials and for actuating the control means to illuminate the signal,

means actuated by the insertion of a coin into the coin chute for extinguishing the signal, and means within the housing operated by the dials for halting the operation thereof and means also actuated by the dials for re-energizing the signal to illuminate the same when the parking period has expired.

17. A coin receiving parking device including, a housing having alined openings therein, rotatable time indicating dials within the housing and visible through said openings, each dial having an aperture therein, which apertures are alined, a coin chute leading past the apertures in the dials, means for retaining a coin in said chute in alinement with said apertures whereby the coin and dials are visible through the openings in the housing, an electrically operated signal carried by the housing, means for controlling the illumination of the signal, means within the housing actuated by the entrance of a vehicle into the parking space adjacent the housing for operating the dials and for actuating the control means to illuminate the signal, means actuated by the insertion of a coin into the coin chute for extinguishing the signal, means within the housing operated by the dials for halting the operation thereof and means also actuated by the dials for re-energizing the signal to illuminate the same when the parking period has expired, and means within the housing actuated by the removal of the vehicle from said space for returning the dials to a starting position, and for means also actuated upon the removal of the vehicle from the parking space for releasing the coin from its position in alinement with the apertures in the dials.

18. A parking device including, a housing, a timing mechanism mounted within the housing, an electrical coil for actuating the timing mechanism, a magnet mounted to swing in the lower end of the housing, an electrical switch adapted to be engaged by the magnet when the same is swung due to the entrance of a vehicle into the space adjacent the housing for closing an electrical circuit to the coil to actuate the timing mechanism, a second electrical switch actuated by the time indicating mechanism when the parking period has expired to break the circuit to the coil and halt actuation of the mechanism, a release coil for permitting the time indicating mechanism to return to a starting position, and a third electrical switch adapted to be closed by the magnet when the same returns to its original position upon the removal of the vehicle from the parking space for energizing said release coil.

19. A coin receiving parking meter including, a housing, an electrical signal mounted on the housing and visible from any direction exteriorly of said housing, a magnet in the lower end of the housing and arranged to be swung by the entrance of a vehicle into the parking space adjacent thereto, a switch adapted to be engaged by the magnet when the same is in a normal position for closing an electrical circuit to the signal to illuminate the same in a particular manner, a second switch adapted to be engaged by the magnet when the same is swung by the entrance of a vehicle into the parking space adjacent the housing for closing another electrical circuit to the signal to change the illumination thereof, a coin chute within the housing for receiving a coin, and means within

said chute for extinguishing said signal when a coin is inserted.

20. A coin receiving parking meter including, a housing, an electrical signal mounted on the housing and visible from any direction exteriorly of said housing, a magnet in the lower end of the housing and arranged to be swung by the entrance of a vehicle into the parking space adjacent thereto, a switch adapted to be engaged by the magnet when the same is in a normal position for closing an electrical circuit to the signal to illuminate the same in a particular manner, a second switch adapted to be engaged by the magnet when the same is swung by the entrance of a vehicle into the parking space adjacent the housing for closing another electrical circuit to the signal to change the illumination thereof, a coin chute within the housing for receiving a coin, an electric switch connected in the electrical circuit of the signal, means within said chute engageable by the coin and adapted to engage the switch to open the same for extinguishing said signal when a coin is inserted, a time indicating mechanism within said housing, and means actuated by said mechanism for again illuminating the signal when the parking period as indicated by said element has expired.

21. A parking device including, an elongate housing, a time indicating mechanism in the upper end of the housing, a coin chute and passage leading from the upper end of the housing to a point below the time indicating mechanism, the housing having an elongate opening in one side thereof below the indicating mechanism, whereby access to the interior of the housing may be had, a coin receptacle within this portion of the housing, a sleeve slidable on the housing for closing said opening, and means for locking said sleeve in position closing said opening.

22. A coin receiving parking device including, a housing, a timing mechanism within the housing, an electrically operated signal carried by the housing and visible from any direction exteriorly of the housing, means for dimly illuminating the signal when a vehicle is not parked within the parking space adjacent the housing, means embedded in the parking berth, and actuated by the entrance of a vehicle into the parking space for operating the timing mechanism and for imparting a flashing illumination to the signal to indicate that the vehicle is properly parked, and means actuated by the insertion of a coin into the device for extinguishing the signal.

HERMAN S. JOHNS.
